GRIPPING DEVICE

Peter Borowski, Detroit, Mich., assignor of one-half to Joseph Bargilewicz and Mitchel Kulbaka, both of Detroit, Mich.

Application December 18, 1933, Serial No. 702,946

4 Claims. (Cl. 81—3.1)

This invention relates to appliances for assisting in the opening and handling of screw-topped containers, such as the preserving jars of the so-called "Mason" type having screw tops and used for home and other preserving of foods in relatively small quantities, but suitable for use as well in connection with cans and other receptacles having lids removable by turning.

An important object of the invention is the provision of means whereby such jars or other containers having screw tops may be tightly sealed and easily opened, and whereby in addition they may be conveniently handled even while hot.

A further object is the provision of a simple, compact and easily operable device of the indicated character by which the screw top of a can or jar head may be tightly gripped without requiring the user to handle the can or jar to apply the device. Another object is the provision of such a tool by means of which a can or jar top may be so firmly grasped that the jar or can may be safely handled by means of the device.

Still another object of the invention is the provision of a device for turning the screw tops of containers which is attachable more firmly to and enables the application of greater leverage upon a top to be turned than has been possible with devices of this character heretofore available.

Other objects and advantages will be apparent from the following description wherein reference is made to the accompanying drawing illustrating preferred embodiments of my invention and wherein similar reference numerals designate similar parts throughout the several views.

In the drawing:

Fig. 1 is a plan view partly broken away of an appliance constructed in accordance with the principles of this invention.

Fig. 2 is a similar view showing the working parts in a different position.

Fig. 3 is a detailed plan view of the ratchet mechanism.

Fig. 4 is a section taken substantially on the line 4—4 of Fig. 2, and looking in the direction of the arrows.

Fig. 5 is a side view of the device; and

Fig. 6 is a similar side view taken looking in the opposite direction and showing the device positioned for use in conjunction with a jar, indicated in dotted lines.

In the drawing reference character 10 designates the fixed portion of a two-part handle, the movable portion of which is designated 11. The fixed handle carries at one extremity a head por-

tion formed of spaced plates 12—12' having an arcuate edge adapted to substantially conform to the curvature of the top of a can or jar, such as the familiar Mason jar used for home canning and the like. Between the spaced plates 12—12' carried by the head or jar-engaging end of the device is arranged a ratchet mechanism operable by means of the swingable handle 11, which is fulcrumed on the shaft 14 of the ratchet wheel 15, being loosely mounted on said shaft by means of a slotted connection, as at 17.

The handle 11 carries rigidly a pawl 19 engageable with the teeth of the ratchet wheel to turn the same when the handle is swung while at one end of its slotted connection (17) with the ratchet shaft but movable to free the teeth when the handle is moved radially outwardly away from the shaft to the other end of such slotted connection.

Another pawl 20, also pivoted in the head portion between the plates 12—12', is swingable about its supporting pin 21 into and out of engagement with the teeth of ratchet wheel 15. Pawl 20 is provided with an integral trigger arm 22 by means of which it may be manually released, and a lever portion 23 extending to a position rendering it engageable by the handle 11 when the latter is moved into sufficiently close proximity to the handle 10. When the handle sections are urged together, as they are when both grasped at once in the natural and most convenient manner, such engagement of the swingable handle section 11 with the lever arm 23 acting to force the pawl 20 into engagement with the ratchet teeth and so hold the ratchet against movement. When the swingable handle section is free of the arm 23, however, the pawl may be released by pressing upon trigger 22, although the pawl remains in engagement with the ratchet until so released, and likewise remains released until again forced into action by the swingable handle, inasmuch as no spring or equivalent means tends to hold the pawl in either position.

Secured at one extremity to the shaft 14 carrying the ratchet wheel is a ribbon-like spring clamping element 25, which may be formed of clockspring or similar material and which tends to straighten when relaxed. The clamping element is looped beyond the end of the head in the manner shown in Figs. 1 and 2 and secured at its free extremity 40 to a pin 26 extending between the plates 12—12' near one end of the head portion.

A stop or abutment 30 carried by and project-

ing centrally from the upper head plate 12 is adapted to engage the jar top (designated 32) in the manner indicated in Fig. 6, to limit downward movement of the device when applied to 5 the jar top.

When both ratchets are released, the tendency of the clamping strap 25 to straighten causes it to unwind from the ratchet shaft, rotating the latter, and to assume the extended position indicated in Fig. 2. A guide pin 36, also carried by the head portion and extending between the plates 12-12' at the opposite end of the head from anchor pin 26, limits separation of the leg portions of the looped strap. It will be seen that 15 by turning the ratchet and so the ratchet shaft, by means of the swingable handle section 11, the strap may be drawn inwardly and so tightly clamped around a jar top, over which it is initially positioned in the manner indicated in Fig. 20 6; and that upon completion of each inward swinging movement in the handle section 11, the pawl 20 is forced thereby into engagement with the ratchet teeth, to hold the ratchet during reverse movement of the swinging handle. When 25 the clamping strap has in this manner been drawn tightly about the jar cover, the cover may be tightened or loosened by a simple turning movement of the handle sections 10-11 as a unit. When it is desired to release the cover it is merely 30 necessary to press the trigger 22 and so release the pawl 23. This movement also moves the handle section 11 away from the fixed handle section 10 if it happens to be so close to the latter as to be within the path of movement of the 35 arm 28, and so simultaneously releases the pawl 19. The tendency of the strap to straighten then causes it to unwind from the ratchet shaft, while turning the latter and the ratchet wheel, thus quickly loosening the strap and permitting the 40 removal of the appliance from the cap.

Due to the firmness with which the lid may be grasped by means of this apparatus, it may safely be used as a handle for carrying jars from place to place, as well as for tightening and re- 45 moving covers.

While it will be apparent that the illustrated embodiments of my invention herein disclosed are calculated to adequately fulfill the objects and advantages primarily stated, it is to be understood that the invention is susceptible to variation, modification and change within the spirit and scope of the subjoined claims.

What I claim is:

1. In a device of the character described, a 55 handle portion, a looped flexible clamping element connected to and projecting from the handle, and means carried by the handle portion for drawing upon at least one end of said clamping element and for holding the drawn end against 60 undesired outward movement, said holding means

comprising a ratchet and pawl and an additional handle movable relatively to the first and engageable with both the ratchet and pawl when moved to different positions to control the movement of both. 5

2. In a gripping device, a fixed handle, a looped gripping element carried by and projecting from the handle, and means carried by the handle for moving a portion of the gripping element to change the dimensions of the loop, and for securing the element and so the loop against undesired movement, said means including a movable handle carried by the fixed handle, a ratchet wheel connected to the gripping element, a pawl carried by said movable handle and releasably engageable with said ratchet wheel, and a locking pawl carried by the fixed handle and also operable by the movable handle. 10 15

3. In a device of the character described, a main handle, a looped flexible gripping element 20 connected to and projecting from said handle, means including a winding element upon which said gripping element may be wound, said gripping element tending to straighten and so unwind from the winding element when relaxed, 25 and means for moving, releasing and controlling movement of the gripping element, comprising a ratchet wheel connected to said winding element, a second operating handle also connected to said winding element for turning the same, pawl means 30 carried by said second handle and releasably engageable with the ratchet wheel, and additional pawl means carried by the main handle and also engageable with said ratchet wheel and movable independently of said main handle but engageable 35 and actuatable by the second handle upon movement of the latter to a predetermined position. 35

4. Gripping means including a main handle, a looped gripping element carried by and projecting from said handle, and means carried by said handle for moving a portion of the gripping element to change the dimensions of the loop, and for securing the element and so the loop against undesired movement, said means including a second movable handle pivotally connected to the first mentioned main handle, a ratchet wheel carried by said main handle and connected to the gripping element, a pawl carried by said movable handle and engageable with and releasable from the ratchet wheel, and additional pawl means carried by the rigid handle and also engageable with the ratchet wheel, means for manually releasing said last mentioned pawl means independently, said pawl means being movable into engagement with the ratchet wheel by the movable handle when the latter is thrown to one position. 40 45 50 55
